OTTO GEORG, OF DUSSELDORF, GERMANY

FORGING MACHINE AND THE LIKE

Application filed September 30, 1926, Serial No. 138,634, and in Germany August 5, 1925.

This invention refers broadly to gripping or clamping and jolting or upsetting machines and it refers particularly to a device for effecting the movement of the gripping 5 or clamping die or carriage on horizontal forging machines and the like in which use is made of a longitudinally movable heading die or carriage operated by a main crank on a crank shaft and a gripping or clamping carriage 10 movable substantially at right angle to the heading die and adapted for the clamping of the piece of work under treatment. The invention generally considered comprises novel and improved means of crank 15 and toggle lever type for effecting the movement of the gripping or clamping carriage, and its object is twofold, first, to relieve the heading die of the work of transmitting motion to the toggle lever mechanism which actuates the gripping die, thus preventing violent wear and tear upon the machine due to racking and jamming of such working parts when so coupled and employed, and, second, 20 to provide for the operation of the toggle lever mechanism from an auxiliary crank on the crank shaft so arranged with respect to the main crank and coacting with a toggle lever mechanism comprising at least three sets of toggle lever devices as to secure an 25 easy and smooth working motion of the parts in place of the racking motion referred to, as well as to secure a novel phase change in the working actions of the clamping and heading dies in the cycle of action of the machine 30 whereby certain desirable and important working and commercial advantages are obtained.

In standard machines employing clamping and heading dies as heretofore operated the working parts are so combined, proportioned and timed that a range of movement or time period of travel of the plunger die equal to at least one-half of the full travel of said plunger die in the direction of its working stroke is necessary to effect a movement of the clamping die from open to closed or clamping position. In those commercial machines in which the toggle lever mechanism is coupled to a plunger die operated by a crank upon an actuating crank shaft

the working action is very violent and causes great wear and tear upon the frame and working parts and the timing is such in the cycle of action that the clamping die is closed just before the plunger die engages the work and the effective working stroke of the plunger die is therefore limited and made comparatively short as a result of the phase or timing restriction thus imposed upon it. In other words, the parts of such a machine are subject to derangement and breakage and the plunger die has a very short upsetting action, reduced to less than 50% of its range of travel in a working direction, so that the machine is not only expensive to maintain but is of greater length than should be required in proportion to the useful upsetting stroke obtained. My invention is designed to overcome not only any violent racking actions of a machine in which the toggle lever mechanism is actuated by the plunger die, but also to effect a phase change in the working actions of the clamping and plunger dies, whereby the clamping die is closed on or before the plunger die has completed the first quarter of its travel in the heading direction, thus enabling a long upsetting stroke to be obtained without increasing the length of the machine, or, conversely, to enable a short upsetting stroke, as in prior standard machines, to be obtained in a machine of smaller size and less expensive in construction and operation than a standard machine.

The invention will be further described with reference to the accompanying drawing showing by way of exemplification several embodiments of the principles thereof.

In Figure 1 I have shown for the sake of comparison and diagrammatically the well-known arrangement for the movement of the clamping or gripping carriage according to the previous art, while in Figure 2 the arrangement according to this invention is shown diagrammatically.

In Figures 3 and 4 a form of construction illustrating the lever connection for the gripping carriage is shown respectively in side view and plan view. A modified form of construction is shown in Figures 5 and 6 in two views respectively corresponding to those of

Figures 3 and 4. A third modified construction is illustrated in Figures 7 to 9 showing the total arrangement of the device in connection with a forging machine and respectively in side view, plan view and in a different position of the parts.

With the well-known manner of actuating the clamping or gripping mechanism by means of a bell-crank mechanism coupled to the carriage, the main crank, as appears from Figure 1, and considering the highest point in its orbit of rotation to be the zero or 0° point starts from the 270° dead center position. Inasmuch as at least a 90° degree travel of the crank is necessary for the closing of the clamping jaws, almost half of the working stroke of the machine is lost for an upsetting action as during this part of the working stroke the clamping jaws are being closed. If, however, the clamping or gripping members are operated from a crank arranged in accordance with my invention, and used in conjunction with a triple toggle lever it becomes possible, as illustrated in Figure 2, to start the main crank from a position 45° degrees ahead of the 270° dead center position, or from the 225° point, and the 90° degrees which are necessary for the closing of the clamping jaws are then disposed in such a manner that only a very small portion of the entire working stroke is required for the clamping or gripping operation, while the remainder of the working stroke is employed for the jolting or upsetting operation proper. The advantage of this new arrangement is very obvious, i. e., a greater length of stroke may be obtained in a standard size machine or the stroke may be reduced so as to result in reduced length of the crank drive rods and consequently allowing a shorter and more compact and less expensive construction of the machine to be built. Other advantages are also gained, as hereinafter fully described.

In Figures 3 and 4 a form of construction embodying the principles of my invention is shown. The clamping or gripping carriage 1 for the gripping of the piece of work is linked by means of the pressure link 2 to one arm of the elbow lever 3 adapted to be rotated on the stationary pivot 4. To the other arm of lever 3 the pressure link 5 is operatively connected which link pivotally couples said lever to the auxiliary carriage 6. The auxiliary carriage is operated from the main crank shaft 31 by the knuckle pin 8 and the crank bar or connecting rod 7. The crank or knuckle 8 is situated at a certain angle α in this instance about 135° ahead of the main crank 32, the crank 8 starting at about the 90° point, as indicated in Figure 3 of the drawing, so that the clamping or gripping action takes place while the main crank 32 is moved in the so-called sneaking arc (Fig. 2).

The operation with the construction shown in Figs. 3 and 4 will be readily understood

from the drawing and following description. In the starting position, considering the highest point in the orbit of rotation of crank 32 to be the zero or 0° point, the auxiliary crank 8 is at the 90° point and the main crank 32 at the 225° point, in which positions of the cranks 8 and 32 the clamping die 1 is fully open or retracted and the heading die has traveled seven-eighths of its backward or return travel from the end of its working stroke. On the movement of the crank 8 from the 90° to the 270° position the carriage 6 is moved the full distance of its rearward travel, carrying with it the link 5 which as it moves backwardly also swings outwardly from the dotted line to the full line position shown in Fig. 4, as a result of which combined movements the link has a reducing differential motion transmitting action whereby the 180° angle movement of the crank 8 is converted into a 45° angle movement of lever 3, thus setting or bringing the link 2 and coacting arm 3 into longitudinal alinement and fully closing the clamping die 1. During this clamping-die closing-action of parts 8, 7, 6, 5, 3 and 2 the main crank 32 moves through the 90° arc from the 225° point to the 315° point, on the first-half of which (between the 225° and the 270° points) the heading die is fully retracted and on the second half of which (between the 270° and 315° points) the heading die is moved forward one-eighth part of its heading stroke, so that the clamping die closing portion of the orbit of the crank shaft, equal to one fourth of the range of travel of the plunger die in either direction, is so disposed as to be divided or apportioned between the final eighth portion of the return stroke of the plunger and first eighth portion of the working stroke of said die. The clamping die remains closed during the full period of the remaining seven-eighths part of the working stroke of the plunger die for the reason that during this period of action of the plunger die an idle period or period of dwell of the toggle lever mechanism proper occurs, during which the toggle lever mechanism retains its clamping die setting or closing position, in which position it is practically uninfluenced by the motion of the crank shaft and the plunger die. This follows from the fact that the distance between crank 8 and the pivotal connection between rod 7 and carriage 6 remains substantially the same in the travel of the crank 8 between the 180° point and the 0° point, with small variations which cause but a slight rocking motion of parts 2 and 3 in this portion of the orbit of travel of the crank 8, which rocking motion is insufficient to break the toggle lever lock between parts 2-3 or to release the grip of the clamping die 1 on the clamped work. Thus it will be seen that the main crank and the auxiliary crank and coacting parts of the toggle lever clamping die actuating mechanism are so

correlated that the clamping die will be moved to clamp the work at a time period allowing three-fourths or more of the working stroke of the plunger die to be used for an upsetting action, the toggle lever mechanism being, as a result of the inactive motion of the parts 7 and 8, idle and remaining set to hold the clamping die closed during the remainder of the cycle of operation of the upsetting die.

10 Another modified form of construction is shown in Figures 5 and 6. The crank 9 arranged at about the same distance as in Figure 5 ahead of the main crank 32, acts, by means of a link or pitman rod 10, to transmit its movement to the upper arm of a bell-crank rocking lever 11, from which the movement, by means of the lower arm of said lever and the pressure link 12, is transmitted to the carriage 13 and thence by way of the pressure link 14 to the toggle lever system 15, 16 and in its turn to the clamping slide 17. The threefold toggle lever action is thereby produced by the crank 9 and the pitman rod 10, by the elbow lever 11 and the pressure link 12, 25 and by the pressure link 15 and the pressure link 16.

With this construction the arrangement is such that the auxiliary crank 9 starts its clamping die closing motion at about the 60° point, while the main crank 32 is in the region between the 207° and 225° points, and the crank 9 ends its clamping die closing motion at about the 150° point and begins its clamping die releasing motion at about the 240° point, during which the crank 32 is traveling from the 207° or 225° point to the 270° point on the final part of the return movement of the heading die and from the 270° point to the 297° or 315° point on the fore part of the working travel of the heading die, from which it will be evident that the clamping die closing movement is completed before the heading die has made an eighth portion of its next succeeding working motion. It will also be evident from the foregoing that the crank 9 on its 60°-240° travel pulls the upper arm of lever 11 downward so that said lever makes a 45° counterclockwise rocking motion while crank 9 is moving through the 90° arc from the 60° point to the 150°, on which portion of the 60°-240° travel the other arm of lever 11 and link 12 are straightened out to close the clamping die, and that from the 150° point to the 350° point the crank pin 9 is equidistant from the pivot connecting rod 10 with the lever 11, and that, therefore, between the 150° and 330° points the rod swings on said pivot as a center of motion, the crank 60 9 and rod 10 having an idling action so far as their effect on the lever 11 is concerned, and that from the 330° point to the 60° point the crank pin 9 rocks the lever clockwise back to its original position and in so doing opens 65 the clamping die. While, therefore, the

crank 32 is moving through its 285°-90° arc the clamping die is closed, and during this time the lever and parts of the toggle lever mechanism between the same and the carriage remain idle or in a set position to hold the 70 clamping die closed. When the crank 9 reaches the 60° point the crank 32 will have reached the 207° or 225° point and there will be a repetition of the cycle of action of the operating parts as above described.

In the form of construction according to Figures 7 to 9 the threefold toggle lever action is combined with a special double-operating point bearing of the clamping or gripping carriage. From the crank shaft 18 the main carriage or plunger die 20 is reciprocated by means of the main crank 32 and the pressure rod 19. The crank shaft 18 is provided at its end with a disc 21 carrying an auxiliary stud 22. This knuckle is connected by the link rod 23 to the rocking lever 24 mounted upon a stationary stud 25. By means of the stud 26 a pressure rod 27 is operatively connected to the slide carriage 28 which by means of the two hinged links or 80 levers 29 is operatively connected to the clamping die or carriage 30. The threefold toggle lever action in this modification is effected between the crank 22 and the link or pitman rod 23 and on the other hand between the rocking lever 24 and the pressure rod 27, and between the hinged carriage 28 and the clamping carriage 30 by the intermediary of the two hinged links 29.

The operation, with the construction 100 shown in Figs. 7, 8 and 9, in which the connecting rod 23 is coupled to the lower arm of the bell crank lever 24, instead of to the upper arm of said lever, in which respect the construction differs from the rod and lever connection shown in Figs. 5 and 6, is as follows:

Figs. 7 and 9 show the starting position, at which time the auxiliary crank is at about the 135° point and the main crank 32a may 110 be at a point between the 225° point and the 270° point, and the links 29 lie at an oblique angle between the retracted clamping die 30 and the carriage 28. In the travel of the crank 32a from the 225° point, (at which time the crank 22 is at the 45° point) to the 270° point the heading die 20 is moved the final eighth part of its rearward stroke back to fully retracted position, and in the travel of the crank 32a from the 270° point to the 115 315° point the die 20 is moved the first eighth part of its travel on its working stroke. During the movement of crank 32a from the 225° point to the 315° point, the auxiliary crank 22 travels the 90° arc from the 135° point to 120 the 225° point and in so doing draws backward on the lower arm of lever 24 and rocks said lever through a 45° arc, in which action the upper arm of said lever operates 125 through rod 27 and slide carriage 28 to 130

straighten out the links 29 to the parallel position at right angles to carriage 28 shown in Fig. 9, thereby shifting die 30 to clamping position, which movement of die 30 to clamping position thus occurs on the first eighth 5 part of the working stroke of die 20. The links 29 hold the die 30 in clamping position as long as they (the links) maintain the parallel relation shown in Fig. 9, in which relation they remain until lever 24 is shifted 10 from the thrown position above referred to on its movement back to the reverse position shown in Figs. 7 and 8. Crank 32^a on its clockwise movement from the 315° point to the 90° point performs its effective heading 15 stroke and then, as the clockwise movement of crank 32^a continues, the backward travel of the die 20 begins. During this movement of crank 32^a from the 315° point to the 90° point the crank 22 travels through an idle arc 20 from the 225° point to the 315° point or beyond without transmitting motion through the rod 28 to the lever 24, which, therefore, remains in a position of rest, since in such 25 arc of travel the ends of rod 28 and link 27 coupled to lever 24 oscillate with lever 24 on the pivot of the latter as an axis of motion without transmission of motion to carriage 28, the lever 24 and links 29 being re- 30 tracted on the movement of crank 22 from the 315° point to the 135° point, a large portion of which travel is taken up in shifting the lever 24 to a position in which it acts through rod 27 and carriage 28 to return the 35 links 29 to their normal oblique position and retract the die 30, so that said die 30 remains in clamping position until after the die 20 has completed its upsetting stroke. From the 90° to the 225° points of travel of crank 40 32^a die 20 is moving seven-eighths of the full range of its backward travel and crank 22 again assumes the 225° point position, thus again bringing the parts back to the position shown in Figs. 7 and 8.

45 It will be observed that in each of the several forms of the invention herein disclosed a motion transmitting mechanism consisting of three sets of toggle lever devices is employed in connection with a working auxiliary crank 50 on the crank shaft arranged at a certain angle with relation to the main crank on said shaft, and that in each case the motion transmitting mechanism includes a bell crank lever and a slide carriage or cross-head, one or the 55 other of which is coupled to the auxiliary crank by a connecting rod having alone or in connection with a bell crank lever or other part to which it is coupled certain idle and acting periods and effecting certain motion 60 transmitting actions whereby the objections to the use of clamping die operating mechanism actuated directly by and from the heading die are not only avoided but the ratio of the working (upsetting) range of the 65 plunger die on its working stroke increased

with respect to the ratio of non-working or idle die-closing period range of the plunger die on such stroke, so that a new timing or phase action or periodical variation from prior working actions is produced, whereby 70 (1) a longer gripping action and a longer actual upsetting action may be obtained without increasing the cycle period, or whereby (2) a wider opening and closing action of the clamping die may be secured for gripping 75 large work pieces without increasing the cycle period, or whereby (3) a combination of these advantages may be obtained, i. e., a wider range of movement of the clamping die with a longer range of actual upsetting movement of the heading die, without increasing 80 the cycle period. Obviously, also, the employment of an auxiliary crank and three-fold toggle lever mechanism of the character described gives another and very important 85 advantage, in that a quick gripping action in connection with a short upsetting die stroke may be used if desired and the machine correspondingly shortened, with resultant economy in the initial cost of manufacture as well 90 as in the operation of the machine.

In practice I have found that the use of a single toggle lever device in connection with an actuating crank gives a range of motion equal to 10% of the working stroke of the 95 heading die and that each addition of a toggle lever device after the first increases the motion range to the extent of 20% more, so that by using a working combination of three toggle lever devices a motion transmitting range equal to 50% of the working stroke of the plunger die may be obtained, and I have further found that by employing such a chain of three toggle lever devices in connection with an auxiliary crank set at an angle of at least 45° with relation to the first-named main crank a mechanism properly combined for a motion transmitting range equal to at least 75% of the total range of 100 travel of the heading die, with the proper non-motion, idle or dwell period for the clamping die required for the lengthy gripping period employed, will be produced without further increasing the number of toggle 105 lever devices used in the chain, such arrangement of the cranks giving the proper motion range and phasing or timing of the dies without the use of more than three toggle lever devices, which would otherwise be required.

The invention may find expression in other embodiments and there are no other restrictions in regard to the construction and relative arrangement of the parts except as particularly set forth and pointed out in the 110 appended claims, and it is also to be understood that the toggle lever action may be effected by such a combination of several 115 levers as to produce a manifold toggle lever or knee action.

I claim:

1. In means for operating the heading and die clamping dies of a forging machine, a heading die, a clamping die, a crank shaft having a main crank and an auxiliary crank set at an angle of at least 45° ahead of the main crank, the said main crank being coupled to the heading die for operating the same, and a three-fold toggle lever mechanism connecting the auxiliary crank and the clamping die and coacting with said auxiliary crank on each cycle of action of the machine to start the closing of the clamping die before the heading die has started its heading stroke and to complete the closing of the clamping die before the heading die has completed the first quarter of its heading stroke and to hold it closed during the remainder of such stroke.
2. In means for operating the heading and clamping dies of a forging or like machine, a reciprocating heading die, a reciprocating clamping die, a drive shaft having main and auxiliary cranks offset at an angle of at least 45° with relation to each other, a connecting rod between the main crank and heading die for reciprocating the latter, and a system of at least three toggle lever motion transmitting devices connecting the auxiliary crank and the clamping die and cooperating with said auxiliary crank to start a closing movement of the clamping die while the heading die is being retracted after a heading stroke and to complete the closing movement of the clamping die before the heading die has completed the first quarter of its succeeding heading stroke.
3. In means for operating the heading and clamping dies of a forging machine, a heading die, a clamping die, a crank shaft having a main crank and an auxiliary crank set at an angle of at least 45° with relation to each other, a connecting rod between the main crank and the heading die, a slide carriage, and connecting means between the auxiliary crank and the slide carriage and between the latter and the clamping die, the same comprising a system of at least three toggle lever motion transmitting devices operatively constructed and connected for coaction with each other and with the auxiliary crank to start a closing movement of the clamping die while the heading die is being retracted following a heading stroke thereof and to complete the closing movement of the clamping die before the heading die has completed the first quarter of its succeeding heading stroke while holding the clamping die closed during the remaining three quarters of said heading stroke.

In testimony whereof I affix my signature.
OTTO GEORG.
